UNITED STATES PATENT OFFICE.

ALFRED C. CLARK, OF PHILADELPHIA, PENNSYLVANIA, ASSIGNOR TO U. S. SAFETY APPLIANCE COMPANY, OF BALTIMORE, MARYLAND, A CORPORATION OF MARYLAND.

SAFETY APPLIANCE FOR AUTOMATIC HAMMERS.

1,206,511.

Specification of Letters Patent. Patented Nov. 28, 1916.

Application filed March 17, 1916. Serial No. 84,910.

To all whom it may concern:

Be it known that I, ALFRED C. CLARK, a citizen of the United States of America, residing in the city of Philadelphia, county of Philadelphia, State of Pennsylvania, have invented certain new and useful Improvements in Safety Appliances for Automatic Hammers, of which the following is a specification.

10 This invention relates to a safety device for tools of the reciprocating type, referred to hereinafter as hammers, for use with a snap or set in the form of a riveter, chisel or the like. Such hammers ordinarily consist 15 of a cylinder or barrel which serves as a guide for a tool, the same being actuated by various means known to the prior art.

The description will be confined to the application of the invention to a compressed 20 air hammer, the use of the invention with other types of hammer being obvious in view of this description.

For convenience in changing the snap or set and because it is difficult to devise a convenient and operative fastening, the tool has 25 in many instances been left free, being merely held in position by pressure against the work. However, this practice is open to the objection that if the air is turned on 30 when the set is not on the work, or otherwise held to prevent its release from the barrel, it will be shot from the barrel which results in the loss of the tool and even in injury to workmen and passers-by.

35 Various means have been devised for limiting the motion of the tool. The more recent appliances for this purpose consist of a cup or thimble passed over the end of the barrel and apertured centrally at what may 40 be termed the bottom of the cup to pass the operative portion or end of the set and present an annular shoulder around the aperture to engage the flange or shoulder on the set. Such cups are illustrated in various 45 prior patents, as that to Sheehan, No. 1,125, 890, and Clark, No. 1,055,135.

The object of the present invention is to provide effective means for locking the thimble in position on the end of the barrel, 50 the same being necessarily convenient to operate so that it may be economical of the workmen's time and efficient as a lock in that it presents sufficient resistance to the stroke of the snap to prevent destruction of 55 the lock and release of the snap or set when

the air is turned on and left on for a considerable time in the absence of contact with the tool and with the work. With these points in view, the applicant has produced a locking means consisting of a key or a plurality of keys set transversely to the direction of the stroke and seated in a transverse slot the sides of which are in planes at right angles to the stroke and which slot or slots extend entirely through the cup and well 65 into the metal of the barrel. The key or keys, one to each slot, likewise present surfaces at right angles to the direction of the stroke and fit closely, each in its slot. These keys are for convenience mounted each on a 70 leaf spring which serves to hold them in position when once seated and prevents them from being dislodged accidentally under any condition of operation to which they may be subjected and at the same time permits them 75 to be withdrawn instantaneously to release the set.

In the accompanying drawing I have illustrated a pneumatic hammer to the barrel of which a safety thimble and key constructed 80 in accordance with my invention has been applied.

Figure 1 is a side view, the end of the barrel with the tool or set and the cup being shown in a central section taken on the plane 85 of the axis; Fig. 2 is a side view of the thimble; and Fig. 3 is a transverse section taken on the line 3, 3 of Fig. 1, showing the thimble and keys and barrel.

Referring to the drawing by numerals, 90 the pneumatic hammer or riveter illustrated in Fig. 1 includes a barrel 1 having a handle 2 with an air connection at 3 and a throttle valve lever 4. The barrel as shown, is broken open to show the piston rod 5 and the tool shank 6. The shank terminates in a collar 7 presenting a shoulder 8 toward the barrel and a shoulder 9 toward the operative end of the tool 10. The operation of the tool and the piston will be well understood from the preamble and are in fact similar to the corresponding parts of other pneumatic riveters. The end of the tool barrel is inclosed by a cup or thimble 11 having an aperture 12 concentric with its axis of a size to form 100 a running fit with the operative end of the tool 10, the inside of the thimble near the end being of sufficient diameter to freely admit the collar 7 on the tool. In this way, 105 an annular shoulder 13 is formed at the end 112

of the thimble to engage the shoulder 9 on the tool, the shoulder 8 on the opposite side of the collar 7 serving to engage the end 14 of the barrel and limit the return stroke of the tool.

It is apparent that if the tool be pressed against the work and the air applied, the vibrations or blows being taken up by the work, there will be no tendency to eject the tool from the barrel but if, by any chance, as must occasionally happen, the air be turned on when the tool is not applied to the work, there will, in the absence of the thimble 11, be nothing to limit the forward stroke and the tool will be immediately ejected with considerable force from the barrel and even in the presence of the thimble 11, if it is not held in position with the utmost rigidity, the battering effect of the rapidly reciprocating tool is such that the thimble will be torn off and the tool released. For the purpose of overcoming this tendency and preventing the release of the tool under any and all circumstances, I have provided the fastening means which is the subject of my invention. This consists of a key or keys 15 seated in the transverse registering slots 16 in the barrel and 17 in the thimble, the slots and key having their abutting surfaces at right angles to the direction of the stroke of the tool and being otherwise so arranged that the greatest possible available surface of metal is presented by both the thimble and the barrel to resist the shearing tendency set up by the hammering of the shoulder 9 of the tool against the annular shoulder 13 of the thimble. Preferably, for the greatest strength with the least metal, the areas of surface transverse to the stroke presented by slots 16 and 17 are equal each to the other. To hold the key or keys in position when once seated and prevent their displacement under all conditions of operation, I provide for each key a stiff leaf spring 19 which carries the corresponding key and is secured at its base 20 to a suitable support normally stationary in regard to the barrel. The spring is preferably made so stiff that its tension cannot be conveniently overcome to withdraw the key from the slot by hand but the bottom of the slot in the barrel is so shaped that the key may be released and seated, passing into and out of the slot in the direction of the length of the slot, by rotating the thimble on the barrel.

It will thus be apparent that I have provided a fastening means so arranged that the thimble is secured to the barrel in a manner to afford the greatest possible resistance to longitudinal displacement. The keys, as shown, are so designed that the slotted portion is approximately half the cross section of the thimble so that one-half the area of the metal is presented to the key and the other half is utilized in resisting the tensile

stress set up in the thimble by the action of the tool when not supported by the work.

I have thus described my invention specifically and in detail in order that its nature and operation may be clearly understood; however, the specific terms herein are used descriptively rather than in their limiting sense and the scope of the invention is defined in the claims:

1. In an automatic hammer having a barrel, a power-driven reciprocating member therein, a tool having a shank in the barrel extending into the path of the said reciprocating member, a safety thimble on the end of the barrel and means for locking the thimble in position on the barrel, consisting of a transverse key having flat surfaces at right angles to the line of reciprocation, the thimble being slotted transversely through its entire thickness, the barrel having registering slots, both slots fitting the key and having surfaces at right angles to the path of the piston to engage the corresponding surfaces of the key. 75

2. A safety thimble for an automatic hammer having transverse slots extending through the entire thickness of the thimble, transverse keys in the slots and a heavy leaf spring for each key secured at one end to the thimble and at the other end to the key. 80

3. A safety thimble for an automatic hammer having transverse slots extending through the entire thickness of the thimble, the slots presenting on one side a surface equal to substantially one-half the cross-section of the thimble, transverse keys in the slots and a heavy leaf spring for each key secured at one end to the thimble and at the other end to the key. 100

4. In an automatic hammer having a barrel, a power-driven reciprocating member therein, a tool having a shank in the barrel and extending into the path of the power-driven reciprocating member, a safety thimble on the end of the barrel and engaging the tool in its advanced position, means for locking the thimble in position on the barrel consisting of a transverse key having flat surfaces at right angles to the path of reciprocation, the thimble being slotted transversely through its entire thickness and the barrel having registering slots, the slots in the thimble presenting a surface on one side at right angles to the line of reciprocation substantially equal to one-half the cross-section of the thimble, both slots fitting the key and adapted to permit it to be inserted and withdrawn. 115

5. In an automatic hammer having a barrel, a power-driven reciprocating member therein, a tool having a shank also in the barrel and extending into the path of the power-driven reciprocating member, a safety thimble on the end of the barrel and engaging the tool in its advanced position, means 120

for locking the thimble in position on the barrel consisting of a transverse key having flat surfaces at right angles to the path of reciprocation, the thimble being slotted 5 transversely through its entire thickness and the barrel having registering slots, the slots in the thimble presenting a surface on one side at right angles to the line of reciprocation, substantially equal to one-half the 0 cross-section of the thimble, both slots fitting the key and adapted to permit it to be inserted and withdrawn, the surfaces of the slots in the key and the barrel being substantially equal.

5 6. In an automatic hammer having a barrel, a power-driven reciprocating member therein, a tool having a shank in the barrel and extending into the path of the power-driven reciprocating member, a safety thimble on the end of the barrel and engaging the tool in its advanced position, means for locking the thimble in position on the barrel consisting of a transverse key having flat surfaces at right angles to the path of reciprocation, the thimble being slotted transversely through its entire thickness and the barrel having registering slots, the slots in the thimble presenting a surface on one side at right angles to the line of reciprocation substantially equal to one-half the cross-section of the thimble, both slots fitting the key and adapted to permit it to be inserted and withdrawn, the slots in the barrel having their bottom surface adjoining the outer cylindrical surface of the barrel so that the keys may be withdrawn from the slots in the barrel by rotating the thimble relatively to the barrel.

7. In a pneumatic hammer having a barrel and a reciprocating piston therein, a tool having a shank in the barrel and extending into the path of the piston, a safety thimble and means for locking the thimble in position on the barrel consisting of a trans-

verse key having flat surfaces at right angles 45 to the path of the piston, the thimble being slotted transversely through its entire thickness, the barrel having registering slots, both slots fitting the key and having surfaces at right angles to the path of the piston to engage 50 the corresponding surfaces of the key.

8. In a pneumatic hammer having a barrel and a reciprocating piston therein, a tool having a shank in the barrel and extending into the path of the piston, a safety thimble, 55 means for locking the thimble in position on the barrel consisting of a transverse key having flat surfaces at right angles to the path of the piston, the thimble being slotted transversely through its entire thickness, the 60 barrel having registering slots, both slots fitting the key and having surfaces at right angles to the path of the piston to engage the corresponding surfaces of the key, and a leaf spring to which the key is secured, the 65 leaf spring serving to hold the key in position when seated.

9. In an automatic hammer having a barrel and a reciprocating power-driven member therein, a safety thimble on the end 70 of the barrel slotted transversely through its entire thickness, a transverse slot in the barrel registering with the slot in the thimble, a key to engage both slots, having its bearing surfaces transverse to the line 75 of reciprocation of the power-driven member, a spring for forcing the key into the slot, the slot in the barrel having its bottom surface adapted to eject the key from the slot in the barrel, when the thimble is rotated relatively to the barrel.

Signed by me at Coatesville Pa. this 15th day of March, 1916.
